UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION-GEAR.

1,290,324.

Specification of Letters Patent. Patented Jan. 7, 1919.

Application filed March 4, 1918. Serial No. 220,235.

To all whom it may concern:

Be it known that I, JOHN F. O'CONNOR, a citizen of the United States, residing at Chicago, in the county of Cook and State of Illinois, have invented a certain new and useful Improvement in Friction-Gears, of which the following is a full, clear, concise, and exact description, reference being had to the accompanying drawings, forming a part of 10 this specification.

This invention relates to improvements in friction gears.

Heretofore, in one well known type of friction gear employed for railway draft rigging, it has been customary to employ a friction shell, a plurality of friction shoes co-operable therewith, spring means to resist relative movement between the shoes and shell, a wedge, and a single anti-friction 20 roller interposed between each shoe and the wedge. Due to the necessity of keeping down the manufacturing cost, none of the parts above mentioned are machined but are either foundry or forging products. As will be evident, where a single anti-friction roll 25 is interposed between each shoe and the wedge, the pressure transmitted between said elements is necessarily concentrated along single lines with the result that great care 30 must be exercised in the material used and design of the parts in order to insure the necessary strength to withstand the concentrated pressures mentioned. Obviously, if a plurality of anti-friction rollers were used 35 in lieu of the present single anti-friction rollers, the pressure would be distributed over a greater area and would permit lighter 40 designs of the parts, but due to the fact that the parts are practically necessarily foundry 45 and forging products without any machining, difficulty has been experienced in obtaining and maintaining proper contact for a plurality of anti-friction rollers. As will be obvious, while a single roller will remain 50 in proper contact with two opposed surfaces, when two or more anti-friction rollers are interposed between opposed surfaces, if the opposed surfaces are not maintained in proper parallel relation, one of the rollers 55 may be in proper contact whereas the other will not, with consequent imperfection in operation and wear of the parts.

The object of my invention is to provide a simple expedient which will permit the use 60 of a plurality of anti-friction rollers between

opposed pressure surfaces and at the same time insure the necessary proper contact between all of the rollers and the opposed surfaces and also permit commercial manufacture of the parts without the necessity of expensive machining or other operations. 60

In the drawing forming part of this specification, Figure 1 is a part longitudinal, vertical section, part elevational view of a portion of a railway draft rigging showing my 65 improvements in connection therewith. Fig. 2 is a vertical, transverse, sectional view, taken on the line 2—2 of Fig. 1. Fig. 3 is an end view of the improved wedge element looking from the inner end of the wedge to 70 its outer end. Fig. 4 is a detail perspective of one of the friction shoes. And Fig. 5 is an enlarged, sectional view to more clearly illustrate the manner of carrying out 75 the invention.

In said drawing, 10—10 denote channel-shaped center of draft sills of a railway car, to the inner faces of which are secured the usual rear stops 11 and front stops 12 with which co-operate rear and front followers 13 80 and 14, respectively. The draw bar 15 of the draft rigging is connected to the shock absorbing mechanism proper by any suitable means, such as the yoke 16, and all of the parts may be supported by a saddle plate 17. 85

The shock absorbing mechanism or gear proper, as shown, includes a casting A, a circularly arranged series of friction shoes B, a wedge C, main spring D, retaining bolt E and a pair of anti-friction rollers F—F be- 90

tween each shoe and the wedge. The casting A is of general cylindrical form having a friction cylinder or shell 18 at its forward end, a spring casing 19 rearwardly thereof and an integral back wall 20. 95 The spring D is seated within the casing 19 in the usual manner and bears at its forward end against the inner ends of the friction shoes B and a washer 21 which may be mounted within the shoes.

Each of the friction shoes B is provided on its inner side with a wedge face or surface 22 and a roll seat 23 at the outer end of the wedge face 22.

The wedge or pressure-transmitting member C, is provided with a series of wedge faces, one for each of the wedge faces of the friction shoes, and in order to carry out my invention, each face of the wedge is prefer- 105 ably recessed, as indicated at 24, opposite 110

the corresponding wedge face 22 of a friction shoe. The bottom of each recess 24 is provided with a series of shallow grooves 25-25 leaving narrow ridges 26-26 therebetween. In each of said recesses 24 is placed a hardened steel insert 27, the latter being held in place by peening or upsetting the edge portions of the recess, as indicated at 28-28. The wedge C is also provided 10 with a roller seat 29 for each of its wedging faces and a pair of anti-friction rollers F-F is interposed between each shoe and the wedge.

In carrying out my invention, the shoes 15 will preferably be made of steel so as to provide a hard bearing surface for the anti-friction rollers which also will preferably be made of steel. The inserts will also be made of steel and the wedge can be made 20 of malleable iron. With the parts assembled as shown, it is evident that upon application of heavy pressure on the wedge C, any unevenness in the relation of the opposed wedge faces of the shoes and wedge C (the latter being of course formed by the steel 25 inserts) will be automatically compensated for by the upsetting of the narrow ribs 26-26 which form the backing for the steel inserts, it being remembered that the said 30 ribs 26 are of course, of malleable iron. In this manner, the steel inserts will be brought to their proper relation with respect to the opposed wedge faces of the shoes so that the device can be comparatively cheaply manufactured and slight inequalities in manufacture overcome in the actual operation of the mechanism, and I am enabled to obtain all the advantages of the use of a plurality of anti-friction rollers to thereby distribute the 35 pressures over a larger area and avoid the concentration heretofore encountered in friction gears of this general type.

I claim:

1. In a friction shock absorbing mechanism, the combination with a friction shell, 45 of friction shoes coöperable therewith and having wedge faces, spring means for resisting relative movement between the shoes and shell, a wedge member of relatively soft metal, inset bearing plates of relatively hard

material on said wedge member and disposed opposite the wedge faces of the shoes, a plurality of anti-friction rollers interposed between each of said plates and the corresponding wedge face of a friction shoe, portions of said wedge member on which said bearing plates are mounted being slightly cut away in parts to thereby facilitate deformation of said portions and permit adjustment of said plates thereon into parallelism with the opposed wedge faces of the 55 shoes.

2. In a friction shock absorbing mechanism, the combination with a friction shell, of friction shoes coöperable therewith, 60 spring means resisting relative movement between the shoes and shell, a wedge member, a plurality of anti-friction rollers interposed between each shoe and said wedge member, said wedge member and shoes having opposed bearing faces for the anti-friction 65 rollers, one set of said bearing faces being formed by inserts of relatively hard material, and means adapting said inserts to automatically adjust themselves by deformation 70 of the metal on which they are seated, upon the application of pressure.

3. In a mechanism including a pair of elements adapted to have pressure transmitted from one to the other, the combination with a plurality of anti-friction rollers 75 interposed between said elements, one of said elements being made of relatively hard metal and provided with an integral bearing surface for said rollers, of an inset relatively 80 hard bearing piece for said rollers in the other of said elements, the last named element being formed of relatively soft metal, the portion of the last named element against which the inset piece bears, being provided 85 with a series of relatively narrow spaced ribs to thereby permit deformation of said ribs for the automatic adjustment of the inset 90 piece upon transmission of pressure between the two elements.

In witness that I claim the foregoing I have hereunto subscribed my name this 14th day of Feb., 1918.

JOHN F. O'CONNOR.
